BOOK COVERS
Sydney S. Leibowitz, 100 Westerleigh Road,
New Haven, Conn.
Filed Mar. 15, 1963, Ser. No. 265,477
4 Claims. (Cl. 281—34)

The present invention relates, in general, to book covers and, in particular, to book covers which can be utilized for advertising purposes.

It is an object of the present invention to provide a transparent book cover or jacket which is adapted to be readily and easily slipped on or off a book or a magazine and which includes portions outside the book covering areas which are adapted to contain advertising material.

It is another object of the present invention to provide a cover or jacket of the described type which is formed from a single blank of transparent sheet material, which blank is provided with the advertisement receiving portions.

It is another object of the present invention to provide a cover or jacket from a blank of the described type, which blank includes portions which form pockets for receiving the cover of the book or the cover pages of a magazine and portions as extend beyond said pockets to receive advertising material.

It is a further object of the present invention to provide a cover or jacket of the described type having pockets to receive a book cover and at least one auxiliary pocket for a pad or the like.

It is a still further object of the present invention to provide an auxiliary pocket on the outer surface of the book cover which can be folded and secured in position against such outer surface.

Other and further objects and advantages of the present invention will become readily apparent to those skilled in the art from a consideration of the following specification taken in connection with the appended drawings which illustrate the best modes presently contemplated for carrying out the invention.

In the drawings:

FIGURE 1 is a plan view of a sheet material blank utilized to form a book cover or jacket pursuant to the present invention;

FIGURE 2 illustrates a book jacket formed from the blank shown in FIGURE 1;

FIGURE 3 is a sectional view taken on the line 3—3 of FIGURE 2;

FIGURE 4 is a view similar to FIGURE 2 and illustrates a modified book cover or jacket;

FIGURE 5 illustrates another form of book cover pursuant to the present invention which is adapted to be used with various different sizes of books, and shows a book on which the cover is provided;

FIGURE 6 illustrates a book provided with a simplified cover pursuant to the present invention;

FIGURE 7 illustrates a cover similar to that shown in FIGURE 6, which is adapted to accommodate books of different thicknesses;

FIGURE 8 is a fragmentary view which illustrates a modified form of sheet material blank; and

FIGURE 9 is a perspective view of a book provided with a cover formed from the blank shown in FIGURE 8.

Referring now to the drawings in detail, FIGURE 1 shows a blank 10 which is utilized to form the book, or magazine, jacket or cover 12, pursuant to the present invention. The blank 10 is formed of transparent flexible, preferably plastic, sheet material, such as a vinyl plastic. As here shown, the blank 10 comprises a body portion 14 provided with integral side flaps 16

2

and 18, an integral bottom edge flap 20, and a pair of upper edge laterally spaced integral projections 22 and 24. The side flaps 16 and 18 are foldable on their respective fold lines 26 and 28, and the bottom edge flap 20 is foldable on the fold line 30.

In forming the book jacket or cover 12, the flaps 16 and 18 are folded on their respective fold lines 26 and 28 and are heat sealed to the body portion 14 to form the upper heat sealed edges 32—32, adjacent to the upper edge 36 of the jacket and the lower heat sealed edges 34—34 adjacent to the lower edge 38 of the jacket. The sealed flaps 16 and 18 define enclosures or pockets 40 and 42 having inner longitudinal pocket openings 44 and 46, respectively. The bottom flap 20 is folded up on its fold line 30 and is heat sealed along its side edges 48 and 50, to define a pocket 52 having an upper edge opening 54.

Pursuant to an important feature of the present invention, the upper horizontal portion 56 of the book cover, which is defined between the top edge 36 and the upper edges 32 of pockets 40 and 42, provides an advertising area 58 which is adapted to be suitably provided with advertising indicia 58. Similarly, the lower horizontal portion of the book cover, between the bottom edge 38 and the bottom edge 34 of pocket 40, extending to the inner edge 48 of pocket 52, provides an advertising area 60 which is adapted to be suitably provided with advertising indicia 58. The advertising indicia is preferably provided on the blank 10 before the cover 12 is formed therefrom. Since the blank 10 is transparent, the advertising indicia 58 may be provided on either surface thereof.

The projection 22 is utilized to form a carrying loop 62 for the cover 12. The loop 62 is formed by heat sealing the free end 64 of projection 22 to the body portion 14 of the blank 10. The other projection 24 functions as a book mark simply by bending it downwardly at upper edge 36 to the broken line position thereof shown in FIGURE 2.

40 A book or a magazine BM may be readily provided with a cover or jacket 12 by simply inserting the sections of the book cover 68 or the outer cover pages of the magazine, into the pockets 40 and 42 through the pocket openings 44 and 46, respectively, as shown in FIGURE 6. The latter figure shows a book cover 66 which is similar in all respects to the book cover 12 except for the auxiliary pocket 52, the loop 62 and the book mark 24 which are omitted from cover 66. It will be noted that the omission of pocket 52 increases the size of the lower advertising portion 60 in cover 66 so that it is substantially the same size as the upper advertising portion 56.

It will be noted that the advertising material 58 is readily visible when the book is provided with the cover or jacket of the present invention. Furthermore, it is within the concept of the present invention to provide a book cover 66 in which either the upper advertising portion 58 or the lower advertising portion 60 is omitted from the cover which would have its upper edge 36, or its lower edge, 38, as the case may be, aligned with the upper pocket edges 32 or the lower pocket edges 34, as the case may be. It will be understood that the auxiliary pocket 52 can be utilized to hold a pad, pencils, or the like which may extend outwardly from the pocket opening 54 to overlie the pocket 42, so as not to interfere with the pages of the book or magazine.

Referring now to FIGURE 4 in detail, there is shown a modified form of book cover 68. Book cover 68 may be similar to either book cover 12 (without loop 62 and book mark 24) or book cover 66. In either case the upper advertising portion 56 is folded upon itself and heat sealed to the blank body 14 at the free edge 70 of said portion 56, above the upper edges 32 of the pockets 40

and 42. When so folded upon itself and sealed to the blank body 14, the upper portion 56 will define a tunnel 72 into which there is removably insertable a strip 74 provided with suitable advertising indicia 53. The tunnel may be open at both ends thereof or closed at one end thereof. In either case, the strip 74 may be changed, as desired, to provide different advertisements. In the embodiment of the book cover 68, provision is made for a book mark which is heat sealed to the sealed edge 32 of pocket 42.

Referring now to FIGURE 5 in detail, there is shown a book cover 78 which, as here shown, is similar to book cover 66 in FIGURE 6. Book cover 78 is adapted to accommodate books of different cover size. For this purpose, in lieu of the pocket 42, there is provided a flap 80 which is sealed to the book cover 78 only at its upper and lower edges 82 and 84 and is unsealed at its side edges 86 and 88.

When utilizing the jacket 78, one side of the cover 68 of the book or magazine BM is inserted into the pocket 40, as in the previously described jackets, and the other side is inserted under the flap 80 between the edge 86 of the flap and the underlying portion of the jacket 78. If the cover 68, in the open condition thereof as shown, has a greater horizontal dimension than the horizontal dimension of the open book jacket 78, the free marginal edge 90 will project beyond the side edge 88 of flap 80 and beyond the associated side edge 92 of jacket 78. In this manner, the jacket 78 can be used with books which are larger than the jacket.

Referring now to FIGURE 7 in detail, there is shown a book cover or jacket 94 which can accommodate books of different thicknesses. As here shown, jacket 94 is substantially similar to jacket 66. However, the spine 96 of jacket 94 is provided with corrugations 98 which make the spine expandable so that both relatively thick and relatively thin books are accommodated by the jacket 94.

Referring now to FIGURES 8 and 9 in detail, there is shown a book cover or jacket 100 formed of a blank 102. Blank 102 is substantially similar to blank 10 having a body portion 14 provided with flaps 16 and 18 which form pockets 40 and 42, respectively when sealed to the body portion, as previously described, to receive a book or magazine BM in the same manner. The jacket 100 is provided also with an upper advertising extension or portion 56 and with a lower advertising extension or portion 60, beyond the upper pocket edges 32 and the lower pocket edges 34, respectively. Pursuant to one feature thereof, the blank 102 is provided with biased edges 104 at the corners thereof, rather than with the corner edges 106 as in blank 10. When the blank 102 is formed into the book jacket 100, the biased edges 106 thereof facilitate the thumbing of the enclosed book by the user, as will be readily apparent from FIGURE 9.

In lieu of the flap 20 which was utilized to form an inner pocket 52 as in FIGURE 2, the blank 102 is provided with a projecting flap 108. Flap 108 is provided with a fold line 120 to form an outer surface pocket 110 on the jacket 100. More specifically, the flap 108, when bent along fold line 120 at the outer surface of the jacket, is heat sealed along its outer edges 114 and 116, the fold line forming a closed bottom 118. The pocket 110 has a top opening 122 and is provided with a male snap fastener element 124 adjacent to its bottom 118. A cooperating female snap fastener element 126 is provided on the cover. Pocket 110 is adapted to hold a pad or the

like. The pocket can be folded upwardly onto the jacket and retained in position thereon by engagement of the snap fastener elements.

From the foregoing, it will be apparent that I have provided a highly novel, efficient and inexpensive book cover or jacket. It will be understood that various changes or modifications may be made therein without however departing from the concept of the present invention as set forth in the appended claims.

I claim:

1. A book jacket comprising a body portion formed of transparent flexible sheet material, said body portion being provided on one surface thereof with a pair of laterally spaced book cover enclosures, said enclosures each having an opening extending between the upper and lower edges of said jacket, and said enclosures having closed upper and lower marginal edges extending transversely of said openings, and an advertising extension provided on said jacket between associated closed marginal edges of said enclosures and the adjacent edge of said jacket, said advertising extension comprising a tunnel in which an advertising strip is removably insertable.
2. A book jacket as in claim 1, said tunnel being closed at one end thereof.
3. A book jacket comprising a blank of transparent flexible sheet material having a body portion and a pair of integral lateral extensions provided on said body portion, said extensions being folded over upon said body portion and secured thereto along the upper and lower edges of said extensions to define a pair of book cover pockets, and said body portion having a marginal edge spaced outwardly from adjacent marginal edges of said pockets to define a free unobstructed surface portion extending between opposite side edges of said body portion for receiving advertising material, said surface portion defining a tunnel in which an advertising strip is insertable.
4. A book jacket comprising a blank of transparent flexible sheet material having a body portion and a pair of integral lateral extensions provided on said body portion, said extensions being folded over upon said body portion and secured thereto along the upper and lower edges of said extensions to define a pair of book cover pockets, and said body portion having upper and lower marginal edges spaced outwardly from the associated upper and lower edges of said pockets to provide a pair of free unobstructed surface portions on said body portion which extend between opposite side edges of said body portion to define advertising extensions, each of said surface portions defining a tunnel in which an advertising strip is insertable.
